United States Patent Office

Des. 223,551
Patented May 2, 1972

223,551

ANCHOR FOR BOATS

Laverne O. Persinger, Burbank, Calif., assignor of fractional part interest to Merle L. Persinger

Filed Nov. 28, 1969, Ser. No. 20,297

Term of patent 14 years

Int. Cl. D12—16

U.S. Cl. D71—1

FIG. 1 is a perspective view of an anchor for boats, showing my new design;

FIG. 2 is a side elevational view; and

FIG. 3 is a bottom view, taken in the direction of the arrow 3 in FIG. 1.

I claim:

The ornamental design for an anchor for boats, as shown.
